SURFACE CONDENSER AND SUPPORT
THEREFOR

John F. Grace, Arlington, N. J., assignor to
Worthington Corporation, Harrison, N. J., a
corporation of Delaware

Application November 15, 1951, Serial No. 256,558

8 Claims. (Cl. 257—43)

1

This invention relates to surface condensers employed for condensing steam in power plants and more particularly to novel means for supporting the additional weight of a condenser occasioned by cleaning fluid during the cleaning of the exterior of the tubes of the condenser. In certain surface condenser installations it is necessary, to maintain maximum heat transfer efficiency, to clean the exterior of the tubes of the condenser periodically and this is done by filling the shell of the condenser with a suitable cleaning fluid. Owing to the large size of such condensers the volume of cleaning fluid required imposes considerable weight to be supported and to support such extra weight from the turbine exhaust connection or to provide for adjustment of support plates or blocks to compensate for such additional weight imposes serious hazards especially if the support plates or blocks are not properly restored to normal operating conditions of the condenser after the removal of the cleaning fluid.

The present invention contemplates a structure whereby the additional weight of the cleaning fluid will be supported directly from the floor or foundation upon which the condenser is mounted, thus freeing the connection to the exhaust of the turbine and the normal supports of the condenser of the strains or stresses imposed by the additional weight of the cleaning fluid, and eliminating the need of additional supporting springs, support plates or blocks and their adjustment or regulation during and after the tube cleaning operation.

With these and other objects in view, as may appear from the accompanying specification, the invention consists of various features of construction and combination of parts, which will be first described in connection with the accompanying drawings, showing a surface condenser of a preferred form embodying the invention, and the features forming the invention will be specifically pointed out in the claims.

In the drawings:

Figure 1 is a cross section through a surface condenser constructed in accordance with the present invention.

Figure 2 is a horizontal section taken on the line 2—2 of Figure 1.

Figure 3 is a fragmentary section of a slight modification of the invention.

Figure 4 is a fragmentary section of a further modification of the invention, and

Figure 5 is a fragmentary section of a still further modification of the invention.

Referring more particularly to the drawings, a surface condenser of approved construction is shown which includes the shell 1 having a plurality of tubes 2 therein through which the cooling medium is circulated for condensing steam which enters the shell through the inlet 3. As is usual in such condenser installations steam is delivered to the condenser from the exhaust of a turbine (not shown) and the condenser is connected directly to the turbine exhaust (not shown) for receiving the steam therefrom. The steam is condensed within the shell 1 and the condensate flows into the hot well 4 and from the hot well 4 through an outlet 5 to the condensate pumps (not shown).

In some installations it is desirable and necessary to clean the exterior of the tubes 2 of the condenser for maintaining proper heat transfer efficiency in the condenser and this is done by filling the shell 1 to a level above the uppermost portion of the tubes 2, with a suitable cleaning fluid. The cleaning fluid within the condenser adds considerable weight and unless such weight is compensated for will impose hazardous strains on the connection of the shell 1 with the turbine exhaust connection and upon the normal supports of the condenser, and the present invention embodies means for compensating for this weight and supporting it so as to relieve normal condenser supports and the exhaust connection free of such strains and to support the weight directly from the foundation on which the condenser rests.

For providing such support, a flat tank 10 is provided beneath the condenser shell 1 which rests directly upon the floor or foundation 11. The tank 10 has an annular flange 12 to which an annular flexible gasket 13 is connected by a ring 14. The gasket 13 is connected to an annular flange 15 formed on the bottom of the shell 14 of the condenser by a suitable attaching ring 16 so that a flexible connection will be provided between the tank 10 and the condenser shell 1 so as not to interfere with the normal supports of the condenser. The top 17 of the tank 10 forms the bottom of the hot well 4 as is clearly shown in Figure

1 of the drawings. A pipe 18 has its inlet opening into the hot well 4 and its outlet opening into the tank 10. A manually operated valve 19 is interposed in the pipe 18. An outlet pipe 20 has its inlet communicating with the interior of the tank 10 and it has a manually operated valve 21 interposed therein. A valved air vent 22 is connected to the tank 10 near its uppermost portion.

When it is desired to clean the tubes 2 and fill the condenser shell 1 with a cleaning fluid, the valves A in the condensate outlet pipe 5 of the condenser are closed and the valve 19 is opened so that the tank 10 will be filled with liquid and this liquid will form a rigid support between the tank 10 and the condenser shell 1 for supporting the weight of the cleaning fluid and the condenser shell directly from the foundation or floor 11 thus relieving the normal supports of the condenser of the additional weight imposed by the cleaning fluid within the shell.

In Figure 3 of the drawings the tank 30 is shown imbedded in the concrete foundation 31 in contradistinction to resting upon the foundation as is shown in Figure 1 of the drawings. The hot well 32 of the condenser 33 has a flat flexible element 34 connected thereto which is also connected to the top of the metal tank 30 providing a yieldable flexible connection between these elements which together with the bottom of the hot well 32 forms a closure for the top of the tank 30. A pipe 35 is connected to the lowermost portion of the hot well 32 and extends into the tank 30 so that when the valve 36 is opened water may flow from the hot well into the tank to fill the tank so that the extra weight in the condenser occasioned by the cleansing fluid will be supported by the water in the tank 30. An outlet pipe 37 communicates with the tank 30 and has a manually operable valve 38 therein. An air vent 39 is also provided for the tank 30 which is controlled by a manually operated valve 40.

In the form of the invention shown in Figure 4 of the drawings the metal tank 10 or 30 is eliminated and the foundation 41 has a recess 42 therein which replaces the tank. The walls of the recess 42 have a suitable connecting element 43 shown in the drawings as a channel iron imbedded therein and the flexible gasket 44 which corresponds to the gaskets 34 and 13 is attached to this connecting element 43 and to the hot well 45 of the condenser for providing the normal yieldable support for this part of the condenser and also forming a sealed closure for the top of the recess 42. When the recess 42 is formed in the concrete foundation 41 it is, of course, waterproofed so as to prevent the leakage of water therefrom. Water to support the extra weight of cleansing fluid in the condenser and to eliminate the flexibility of the connection between the hot well 45 and foundation 41 provided by the flexible element 44 is admitted in to the recess 42 from the hot well through a pipe 46 having a manually operable valve 47 therein. The usual outlet pipe 48 and air vent 49 as shown in Figures 1 and 3 of the drawings are also provided in this form of the invention.

Figure 5 of the drawings shows a slightly different construction wherein the flexible gasket or element 44 is replaced by a stuffing box structure 50 which includes the shell 51 carried by the foundation 52, the packer 53 and the packing material 54 which provides a fluidtight seal between the walls of the recess or tank 55 and the sidewalls of the hot well 56. The recess or tank 55 may be in the form of a waterproofed recess

in the concrete foundation 52 or in the form of a metal tank as shown in Figures 1 and 3 of the drawings without departing from the spirit of the present invention. In this form of the invention shown in Figure 5 the pipe for admitting water into the tank or recess 55, outlet pipe and air vent therefor are provided the same as in the other forms of the invention. It is understood, of course, that when the condenser tubes are being cleaned that the various tanks or recesses 10, 30, 42 and 55 are completely filled with water so as to render the normally flexible connections between the hot well and the foundation rigid to provide a support for the extra weight occasioned by the cleansing fluid.

It will be understood that the invention is not to be limited to the specific construction or arrangement of parts shown, but that they may be widely modified within the invention defined by the claims.

What is claimed is:

1. In a surface condenser embodying a shell, a hollow tank beneath the bottom of the shell, a flexible connection between the tank and shell, an inlet pipe for admitting fluid to said tank, and an outlet pipe for permitting removal of fluid from the tank.

2. In a surface condenser embodying a shell, a hollow tank beneath the bottom of the shell, a flexible connection between the tank and shell, an inlet pipe for admitting fluid to said tank, and an outlet pipe for permitting removal of fluid from the tank, said inlet pipe having its inlet opening into said shell and a valve in said pipe.

3. In a surface condenser, the combination with a foundation for supporting the condenser, of a condenser including a shell, a hollow tank supported by said foundation and beneath said shell, a flexible connection between the tank and shell, an inlet pipe for admitting fluid to said tank whereby the weight of the shell and its contents will be supported from said foundation through said tank, and an outlet pipe for permitting removal of liquid from said tank.

4. In a surface condenser, the combination with a foundation for supporting the condenser, of a condenser including a shell, a hollow tank beneath said shell and resting upon said foundation, a flexible connection between the tank and condenser shell and located between the top and bottom of the tank whereby when the tank is empty said flexible connection will permit movement of the shell relative to the tank, an inlet pipe for admitting fluid to said tank and an outlet pipe for permitting removal of liquid from the tank.

5. In a surface condenser, the combination with a foundation for supporting the condenser, of a condenser including a shell and a hot well, a hollow tank beneath the hot well, a flexible connection between the tank and hot well at the upper extremity of the tank whereby when the tank is empty said flexible connection will permit movement of the shell relative to the foundation, an inlet pipe for admitting fluid to the tank and an outlet pipe for permitting removal of liquid from the tank.

6. In a surface condenser, the combination with a foundation for supporting the condenser, of a condenser including a hot well, means forming a hollow tank beneath the bottom of said hot well, said hot well normally movable relative to the foundation, a pipe connected to the hot well and to said tank whereby the tank may be filled with water from the hot well to prevent move-

ment of the hot well relative to the foundation, and an outlet for water from said tank.

7. In a surface condenser, the combination with a foundation for supporting the condenser, of a condenser including a hot well, means forming a hollow tank beneath the bottom of said hot well, said hot well normally movable relative to the foundation, a pipe connected to the hot well and to said tank whereby the tank may be filled with water from the hot well to prevent movement of the hot well relative to the foundation, an outlet for water from said tank, and means forming a fluid seal between said hot well and tank.

8. In a surface condenser embodying a shell and a hot well, a hollow tank beneath the bottom of the shell, an inlet pipe for admitting fluid to the tank connected to the hot well for delivering water from the hot well to the tank, an outlet pipe for permitting removal of fluid from the tank, and flexible means supporting the shell and hot well.

JOHN F. GRACE.
